UNITED STATES PATENT OFFICE.

POWELL O. ADAMS, OF CAMERON, TEXAS.

RAILWAY-CROSSING.

No. 904,037.

Specification of Letters Patent.

Patented Nov. 17, 1908.

Application filed February 26, 1908. Serial No. 417,821.

To all whom it may concern:

Be it known that I, POWELL O. ADAMS, a citizen of the United States, residing at Cameron, county of Milam, and State of Texas, have invented certain new and useful Improvements in Railway-Crossings, of which the following is a specification.

My invention relates to crossings for railway tracks and particularly to railway crossings to be operated in connection with block signal systems, and the object is to provide crossings which can be easily operated to prevent the pounding of the wheels against the rails and by which a firm and continuous track is provided for every engine, car, or train which may pass and which will be strong and durable.

Other objects and advantages will be fully explained in the following description and the invention will be more particularly pointed out in the claims.

Reference is had to the accompanying drawings which form a part of this application and specification.

Figure 1 is a plan view of the crossing, showing the connection for the passage of a car or train in one direction. Fig. 2 is a plan view, showing one section of the means for making a continuous track by a variation in the actuating mechanism, one of the cylinders being shown in section. Fig. 3 is a vertical cross-section, taken either along the line $x-x$ or $y-y$ of Fig. 1. Fig. 4 is a broken perspective view of one of the stationary portions of the track. Fig. 5 is a plan view, showing the application of the invention for use in rail track frogs. Fig. 6 is a plan view of another variation of the invention applied to frogs.

Similar characters of reference are used to indicate the same parts throughout the several views.

The meeting rails 1 and 2 are preferably made integral with each other. The sections 3, 4, 5, and 6 are stationary and may be made rigid and firm in any suitable manner. The connections between the sections 3, 4, 5, and 6 and the sections 1 and 2 are made by telescoping members. Each connection is made by a short move of element 7 and a long move of element 8. The balls of the rail sections 3, 4, 5, and 6 connect with the mem-

bers 7 by means of tongue and groove joints. The main body portions of the sections may be of the usual form of rails having extended base portions 9 which receive the members 7 and 8. The base portion 9 has a flanged connection 10 which is engaged by the members 7 and 8 which are slidable thereon. The members 7 and 8 are grooved to receive the flanged connections 10. The stationary members and the telescoping members between the tracks are provided with guards 34 which brace the stationary and telescoping members and prevent the displacement of these members.

Means are provided for actuating the members 7 and 8. Fig. 1 shows one method of moving these members. A single operating shaft 11 serves to operate all the members 7 and 8. The shaft 10 is provided with a bevel gear wheel 11. Gear 11 rocks two shafts 12 and 13 by means of bevel gear wheels 14 and 15 rigid on said shafts. The members 7 and 8 which make connection with sections 3 and 5 are directly operated from the shafts 12 and 13. Rods 16 pivotally engage the crank portions of shafts 12 and 13 and are connected to members 8 by I-bolts 17. In this manner when the shafts 12 and 13 are rocked the members 8 may be moved a distance of two inches or whatever distance may be necessary. The members 7 and 8 have their meeting faces set at an angle to each other so that car wheels passing over the same will run on a continuous tread, while passing over the lapped portions of the two members, and a continuous tread is provided at the junctures of the members 7 with the sections 3, 4, 5, and 6 by the tongue and groove connections of the balls of the respective elements. The members 8 have a longer travel than the members 7. The short travel of the members 7 is accomplished by collars 20 and 21 which are rigid on the push and pull rods 16 and the eyebolt 22. The rod 16 moves freely through the bolts 22. The members 8 will thus move one inch in either direction before the member 7 moves at all if the member 8 is arranged to move two inches. In any event the member 7 moves only one half as far as the member 8. Fig. 1 shows the track arranged for a train to pass over the sections 3

and 5. The means for actuating the members 7 and 8 which make connections with sections 4 and 6 are also shown in Fig. 1. The wheels 23 which have face cogs are 5 rigidly mounted on the shafts 12 and 13. Wheels 23 drive the cog wheels 24 mounted on shafts 25. The shafts 25 drive the beveled cogs 26. The bevel cogs 26 drive the bevel cogs 27 which are mounted on the 10 crank shafts 28. The crank shafts 28 drive the push and pull rods 29 which are operatively connected on the crank-shafts 28 and pivotally connected to the members 8 by means of the connection 17. The push rods 15 29 are provided with rigid collars 20 and 21 and run through the eyebolts 22 and operate in the same manner as the rods 16 to actuate the members 7 and 8. Turning the rod or shaft 10 in one direction will rock the shafts 20 12 and 13 to open the passage for a train over the tracks 3 and 5 and to close the passage to trains over the tracks 4 and 6, as shown in Fig. 1. Turning the shaft in the opposite direction will open the members 7 25 and 8 for passage over the tracks 4 and 6 and close the tracks 3 and 5. The members 8 will all be operated simultaneously and the members 7 will all be operated simultaneously.

30 Instead of the gearing shown in Fig. 1, the members 7 and 8 may be operated by compressed air. Fig. 2 illustrates the manner of using compressed air or steam for this purpose. The push rods 16 or 29 may be 35 connected with a piston rod 30 which operates in a cylinder 31. The cylinders 31 are each provided with two connections 32 and 33 for receiving compressed air from a supply source. Compressed air turned in 40 through the connections 32 would disconnect the passage over track 3 and connect the members for passage at right angles to track 3. Turning compressed air in the cylinders 31 through the pipes 33 would connect the 45 members for passage over the tracks 3 and disconnect for passage in the other direction. This same method of shifting telescopic members may be applied to frogs for railway tracks in the same manner as above described, as illustrated in Figs. 5 and 6.

Having fully described my invention, what I claim as new and desire to secure by Letters Patent, is,—

1. A railway crossing comprising meeting rail members rigid with each other at each corner of the crossing, continuous track forming members between said meeting rail members consisting of stationary rail members provided with extended bases and movable rail members mounted on and slidable on said extended bases, and means for actuating said movable members.

2. A railway crossing comprising meet-

ing rail members rigid with each other at each corner of the crossing, continuous track 65 forming members between said meeting rail members consisting of stationary rail members having portions of their bases cut away and provided with extended bases and movable rail members having recesses in the 70 balls thereof to receive the reduced ball portions of said stationary members and mounted on and movable on said extended bases, and means for actuating said movable rail members.

3. A railway crossing comprising meeting rail members rigid with each other at each corner of the crossing and continuous track forming members between said meeting rail members consisting of stationary 80 telescopic members and movable telescopic members in two sections.

4. A railway crossing comprising meeting-rail members rigid with each other at each corner of the crossing and continuous 85 track-forming members between said meeting-rail members consisting of stationary telescopic members and movable telescopic members in two sections, and means for giving a short move to one section of each movable member and means for giving a longer move to the other section of each movable member.

5. A railway crossing comprising meeting-rail members rigid with each other at 95 each corner of the crossing and continuous track-forming members between said meeting rail members consisting of stationary telescopic members and movable members, each movable member being in two sections 100 consisting of an abutting section and a section telescoping with each stationary section, means for moving each abutting section, and means for giving a shorter move to each telescoping section after its co-acting 105 abutting section has commenced moving.

6. A railway crossing comprising meeting-rail members rigid with each other at each corner of the crossing and continuous track-forming members between said meeting rail members consisting of stationary telescopic members and movable members, each movable member consisting of an abutting section and a telescopic section, a rod attached to each abutting section for 115 actuating said section, means for actuating all of said rods simultaneously, and each rod being operatively connected with said telescopic sections for moving said telescopic sections after said abutting sections have 120 commenced to move.

7. A railway crossing comprising meeting-rail members rigid with each other at each corner of the crossing, continuous track-forming members between said meeting rail members consisting of stationary 125

members and movable members coöperating with said stationary members, rotatable crank shafts operatively connected with said movable members for actuating all of said 5 movable members simultaneously, and gearing for driving said crank shafts.

In testimony whereof, I set my hand in

the presence of two witnesses, this 12th day of February, 1908.

POWELL O. ADAMS.
